P. C. MERKER,
FASTENING MEANS FOR CAR DOORS, &c.
APPLICATION FILED JAN. 13, 1913.

Patented Feb. 10, 1914.

2 SHEETS—SHEET 2.

UNITED STATES PATENT OFFICE.

PHILIP C. MERKER, OF CEDAR RAPIDS, IOWA.

FASTENING MEANS FOR CAR-DOORS, &c.

1,086,604.

Specification of Letters Patent. Patented Feb. 10, 1914.

Application filed January 13, 1913. Serial No. 741,865.

To all whom it may concern:

Be it known that I, PHILIP C. MERKER, a citizen of the United States, residing at Cedar Rapids, in the county of Linn and State of Iowa, have invented a new and useful Fastening Means for Car-Doors, &c., of which the following is a specification.

The invention relates to improvements in fastening means for car doors, etc.

10. The object of the present invention is to improve the construction of fastening means for car doors, etc., more especially the means for securing the car door, shown and described in an application filed by me on or 15 about Oct. 19, 1912, Serial No. 726,753, when a car is to be loaded with grain.

A further object of the invention is to provide locking means adapted to securely hold the lower portions of the sections of 20 the car door at their free or meeting edges and effectually prevent the same from being forced apart, whereby the car door is rendered perfectly grain tight at the bottom.

It is also the object of the invention to 25 provide locking means of this character adapted to receive a car seal, so that the bottom locking means cannot be unfastened without plainly disclosing the fact that it has been tampered with.

30. With these and other objects in view, the invention consists in the construction and novel combination of parts hereinafter fully described, illustrated in the accompanying drawings, and pointed out in the claims 35 hereto appended; it being understood that various changes in the form, proportion, size and minor details of construction, within the scope of the claims, may be resorted to without departing from the spirit or sacrificing 40 any of the advantages of the invention.

In the drawings: Figure 1 is a front elevation of a portion of a grain door provided with fastening means, constructed in accordance with this invention. Fig. 2 is a 45 front elevation of the pivoted locking device. Fig. 3 is a vertical sectional view of the same. Fig. 4 is a horizontal sectional view of the pivoted locking device. Fig. 5 is a detail perspective view of the locking arm. Fig. 6 is a detail plan view, partly in section, of the handle which secures one end of the exterior door fastening chain.

Like numerals of reference designate corresponding parts in all the figures of the 55 drawings.

In the accompanying drawings in which,

is illustrated the preferred embodiment of the invention, the car door is constructed substantially the same as that shown and described in the aforesaid application, the upper door thereof being omitted and only portions of the vertical door sections 2, 3, 4 and 5 of the lower or main door being illustrated. The door sections 2 and 3 are hinged together and the door sections 4 and 5 are likewise hinged together forming two sectional doors. The door sections 2 and 5 are slidably connected with vertical pintle rods 8 by hinge elements, composed of two leaves 9 and 10 hinged together by a vertical pintle 11. The vertical pintle rods 8, which are located at opposite sides of the door opening of the car, are supported at intervals by fixed hinge elements or brackets 13, provided with vertically alined eyes to receive the pintle rods 8 and having horizontal slots 14 through which pass bolts 15, or other suitable fastening means for securing the hinge elements or brackets 13 in fixed adjustment.

No claim is made in the present application to the long and short inclined chains, which form the subject-matter of a copending application, filed Oct. 19, 1912, Serial No. 726,753. Neither is any claim made in the present case to the device for attaching the lower end of the long inclined chain to the bottom or floor of the car.

The vertical door section 4 is held against outward movement by a pivoted locking device comprising a locking arm 41 located at the inner face of the door 4 and provided with an integral pivot 42, extending outwardly through the door section 4 and through a bearing opening 43 in a plate or support 44, which is secured to the outer face of the door section 4. The locking arm, which is of a length to project beyond the free edge of the vertical door section 4 and extend over or overlap the adjacent portion of the vertical door section 3, is spaced slightly from the inner face of the door section 4 by an annular boss 45, surrounding the inner end of the pivot and being of a thickness slightly in excess of the thickness of the door section 4 and fitting against the inner face of the plate 44, as clearly illustrated in Fig. 10 of the drawings. The spacing of the locking arm from the inner face of the door 4 prevents the locking arm from binding and enables the same to swing freely to and from its engaging position.

The plate or support 44 is secured to the outer face of the door section 4 by upper and lower bolts 46 and 47, and the nut 48 of the lower bolt is arranged to be engaged by a 5 projection 49 of the locking arm and forms a stop for the same and supports the locking arm in its engaging position, and the locking arm is also adapted when swung upwardly and rearwardly out of engagement 10 with the door section 3 to rest upon and be supported by the nut of the said fastening device.

The pivot 42 is secured in the bearing opening 43 of the plate or support by a cotter pin 49^a piercing the pivot and arranged at the outer face of the plate or support 44 and having its head located beneath the upper portion of an arcuate guard flange 50 when the locking arm is in its engaging position. The guard flange 50, which is formed integral with the plate or support, is spaced from the head of the cotter pin and extends downwardly a distance greater than the arcuate movement of the head of the cotter pin in the pivotal movement of the locking arm in swinging to and from its engaging position. By this construction the cotter pin is effectually prevented from being removed when the parts are assembled and 30 secured to the car door. The parts are assembled before the lower bolt is applied to the plate or support, and when the latter is removed, it will permit the free swinging movement of the locking arm and will enable the head of the cotter pin to be carried 35 beyond the guard flange, so that the said cotter pin may be readily removed if desired. Any other form of detachable stop may, of course, be employed for limiting the 40 movement of the locking arm to retain the head of the cotter pin normally between the terminal portions of the guard flange.

The outer portion 51 of the pivot is reduced and provided with flat side faces to 45 form a wrench receiving portion, and it has a slot or opening 52 adapted to receive a wire 53 of a car seal 54. The wire of the car seal is also passed through a slot or opening 55 in the lower end of a vertically movable bolt 56, consisting of a rounded lower portion and an enlarged upper portion provided with a longitudinal slot 57 through which passes a rivet 58, projecting from a hollow stud 59 and guiding the upper portion 60 of the slidable bolt 56. The upper slotted portion of the bolt fits against the outer end of the stud 59, and it is grooved at its outer face at opposite sides of the slot 57 to receive the head of the rivet 58. The 65 lower rounded portion of the bolt 56 is guided in an opening 60 of an arm 61, formed integral with the plate or support and extending horizontally from the same and located beneath and in vertical alignment with the hollow stud 59. The bolt 56,

which is provided at its upper end with a lip or flange 62 to enable it to be readily grasped, is adapted to be lifted above the horizontal arm 61, which receives a link of a short chain 63, adapted to be retained on the arm 61 by the bolt. When the slidable bolt is lifted out of engagement with the chain receiving arm, it is free to swing on the rivet 58. The other end of the chain is adjustably connected with a keeper consisting of a horizontal handle 64 having terminal attaching portions 65 and an outwardly extending approximately U-shaped intermediate portion, which is provided at its inner face with an L-shaped lug 66, forming a 80 hook-shaped projection and adapted to engage a link of the chain 63. The chain is first placed on the hook-shaped lug 66 and is retained in engagement with the same by the horizontal arm 61 after being placed thereon. The chain is confined on the arm by the vertical bolt, which is sealed in its engaging position, and it will be seen that in order to unfasten the lower portions of the vertical door sections 3 and 4, it will be 90 necessary to break the wire of the seal. This may be done by rotating the pivot with a wrench, or other suitable tool.

What is claimed is:—

1. The combination with a door having 95 door sections, of a locking device comprising a plate or support mounted on one of the door sections, a pivot piercing the plate or support, a locking arm carried by the said pivot and arranged at the inner face of the door and provided with an inwardly extending projection, said locking arm being of a length to extend beyond the door section on which it is mounted so as to engage the inner face of an adjacent door section, a stop arranged in the path of the arm and also in the path of the projection thereof and engaged by the latter to support the arm in its engaging position and adapted also to support the arm when the latter is out of 100 engagement, and means for holding the door section while it is engaged by the locking arm.

2. The combination with a door having 115 door sections, of a plate or support secured to one of the door sections, a locking arm arranged at the inner face of the door and having a pivot piercing the plate or support and provided with a boss of a thickness greater than that of the car door and fitting 120 against the plate or support to space the locking arm from the inner face of the door, said pivot being also provided with an outer polygonal wrench receiving portion, means for limiting the swing of the locking arm, 125 and means for holding the door section, which is engaged by the locking arm.

3. The combination with a door having 130 sections, of a plate or support secured to one of the sections and provided with an

arcuate guard, a locking arm having a pivot 5 piercing the plate or support, a detachable stop arranged in the path of the locking arm for limiting the movement thereof, a removable fastening device piercing the pivot and arranged adjacent to and retained in place by the arcuate guard when the locking arm is limited in its swing by the said stop, said fastening device being adapted to be 10 carried beyond the guard flange when the said stop is removed, and means for holding the door section, which is engaged by the locking arm.

4. The combination with a door including 15 contiguous sections, of a combined handle and keeper mounted on one door section and provided with an interior substantially hook-shaped lug, a plate or support mounted on the other door section and having a projecting arm, a chain detachably engaged at 20 one end with the said hook-shaped lug and having a link at its other end arranged on the said arm, and seal receiving means for retaining the chain in engagement with the 25 said arm.

5. The combination with a door including 30 contiguous sections, of a combined handle and keeper mounted on one door section and provided with an interior substantially hook-shaped lug, a plate or support mounted 35 on the other door section and having a projecting arm, a chain detachably engaged at one end with the said hook-shaped lug and having a link at its other end arranged on the said arm, a slidable bolt piercing the arm and having a seal receiving opening, and a locking arm having a pivot piercing the plate or support and also provided with a seal receiving opening located adjacent to

the opening of the said bolt, said locking 40 arm being arranged at the inner face of one of the door sections and adapted to project beyond the same to engage the other door section.

6. The combination with a door including 45 contiguous door sections, of a plate or support secured to one of the door sections and having a projecting arm, a locking arm located at the inner face of the car door and provided with a pivot piercing the plate or 50 support at a point below the projecting arm thereof and having a seal receiving opening, a slidable bolt piercing the arm and adapted to confine one end of a chain on the same and having a seal receiving opening located 55 adjacent to the opening of the said pivot, and means mounted on the other door section for engaging the other end of the chain.

7. The combination with a door including 60 contiguous door sections, of means mounted on one of the sections for detachably engaging a chain, a plate or support secured to the other door section and provided with a chain receiving arm, a locking arm arranged 65 at the inner face of the door and piercing the plate or support and having an exterior seal receiving portion, and means for retaining the chain on the arm of the plate or support, said means having a seal receiving portion located adjacent to that of the 70 said pivot.

In testimony that I claim the foregoing as my own, I have hereto affixed my signature in the presence of two witnesses.

PHILIP C. MERKER.
